UNITED STATES PATENT OFFICE

2,354,180

HARNESS CONNECTOR FOR LOOMS

Alan E. Brickman, Monongahela, Pa., assignor to
The American Steel and Wire Company of New
Jersey, a corporation of New Jersey

Application March 17, 1942, Serial No. 435,095

11 Claims. (Cl. 139—84)

This invention relates to looms and, particularly, to an improved adjustable harness connector therefor.

There are provided generally, in looms, harness frames by means of which the warp threads are raised and lowered. Each harness frame is usually operated by means of connectors including dobby cords which are secured at one end to the harness frame and extend around sheaves arranged on the loom frame, with the opposite end connected to a suitable actuating means, such as a lever or jack of a dobby. Such connectors must be flexible, at least in the portion extending around the sheave, and they should be adjustable as to their length in order to insure the proper operation of the harness frame in the formation of the shed. That is, the connectors should be adjustable so that the correct position of the warp threads relative to the race may be obtained by adjusting the length thereof. The connectors should also be adjustable so as to provide for such changes as may be necessary due to changes in the weave, wear of the parts of the loom, or adjustment of the actuating mechanism.

Various types of harness connectors have been suggested and used. Many of these connectors were unsatisfactory in that they included too many wear-producing connections and parts, thereby requiring frequent adjustment and replacement of parts and dobby cords. Furthermore, such connectors usually employed two or more dobby cords or straps. Such cords or straps would wear and stretch and cause changes in the shed which, in turn, reflect on the shuttle travel. These cords or straps would then have to be replaced, which was inconvenient, as well as expensive.

Also, the harness frame, in its movement, would tend to transmit a whipping action to the connectors, thereby tending to throw the connectors off the sheaves or result in displacement of the connectors at their connection with the actuating means or jack, which was, of course, unsatisfactory and interfered with production.

Accordingly, it is one of the objects of the present invention to provide an improved harness connector for looms which is simple and inexpensive in its construction and use, and, at the same time, one that is efficient and effective in all respects.

It is another object of the invention to provide an improved harness connector for looms consisting of a minimum number of parts and con-

nctions, thereby reducing maintenance and replacement costs.

It is a further object of this invention to provide an improved harness connector for looms which can be easily and conveniently adjusted as to length so as to insure the proper movement of the harness frames.

It is still another object of my invention to provide an improved harness connector for looms whereby any whipping action transmitted thereto is reduced to a minimum and absorbed thereby so that the connector will not become displaced from its operating position.

Various other objects and advantages of this invention will become more apparent during the course of the following specification and will be particularly pointed out in the appended claims.

In the accompanying drawing there is shown, for the purpose of illustration, one embodiment which my invention may assume in practice.

In this drawing:

Figure 1 is a diagrammatic front elevation of a portion of a loom showing the harness frame and the dobby jack or harness frame actuator, with the improved harness connector of my invention incorporated therewith;

Figure 2 is a longitudinal section through the eye portion at one end of my improved harness connector for connecting the same to the dobby jack or harness actuator;

Figure 3 is a detail view of the opposite end thereof showing the means arranged therewith for adjusting the length of my harness connector;

Figure 4 is an enlarged side elevation of the means for adjusting the length of my harness connector, as shown in Figure 3; and

Figure 5 is a top view of the adjusting means as shown in Figure 4.

Referring more particularly to the drawing, the improved harness connector of my invention is shown in Figure 1, incorporated with a conventional type loom which includes generally a loom frame or arch 2 having adjustable brackets or sheave stands 3 arranged thereon, with each supporting a rotatable sheave 4. There is provided a dobby jack or harness frame actuator 5 having a plurality of spaced apart notches 6 arranged along the outer edge thereof and a harness frame 7 having a pair of hooks 8 arranged along the top edge thereof. It will be understood that the jack or harness frame actuator 5 is actuated reciprocably by mechanism (not shown) so as to move the harness frame 7 in a vertical plane by means of a connecting

means arranged between the jack and the harness frame to which the present invention relates.

The improved harness connector of my invention comprises a longitudinally extending rod-like jack member 9 preferably made of wire and having an eye portion 10 arranged on the outer end thereof. The jack eye portion 10 is preferably a die-cast member which is preferably cast directly upon the end of the rod-like member 9 so as to provide an eye-shaped terminal on the end thereof. On the inner periphery of the eye portion 10 at a point directly opposite the connection of the rod-like member 9 therewith there is disposed a ball-like bearing portion 12. The ball-like portion 12 is preferably a steel bearing ball which is cast in the die metal of the eye portion 10 by the insert method, in a manner similar to that in which the end of the rod-like member 9 is cast therein, as shown in Figure 2 of the drawing.

On the opposite end of the rod-like member, there is positioned a longitudinally extending adjustable member 13 having a relatively large longitudinally extending hole 14 arranged in the inner end thereof. There is arranged along and longitudinally of the member 13 intermediate the length thereof, as shown in Figures 3, 4, and 5 of the drawing, a plurality of spaced apart notches or recesses 15 which are provided to adjust the length of the connector in a manner hereinafter to be described. There is arranged in the upper side of the member 13, and communicating with the notches 15 therein, preferably a longitudinally extending groove 15a having a contour similar to that of the rod-like member 9 with which it cooperates. The end of the rod-like member 9 opposite that from the end having the eye portion 10 arranged thereon, extends through the hole 14 in the end of the adjustable member 13 and into the groove 15a thereof, and there is arranged on the extreme end of the rod-like member 9 a hook portion 16 which is adapted to fit in and cooperate with any one of the notches or recesses 15 in the member 13 in order to adjust the length of the connector, as shown in Figures 3 and 4. That is, the end of the rod 9 is bent outwardly substantially perpendicular to the axis of the rod-like member 9 so as to provide a finger-like projection on the extreme end thereof.

In the extreme outer end of the adjustable member 13 there is arranged an elliptical-shaped hole 17, and between that portion of the member 13, in which the hole 17 is arranged, and the notches or recesses 15 arranged therein, there is disposed, on one side of the adjustable member 13, preferably a wedge hook-shaped portion 18, for a purpose hereinafter to be described.

The improved harness connector of my invention is assembled on the loom mechanism in a manner clearly shown in the drawing. The eye portion 10 fits over and around the dobby jack 5 of the loom, and the ball-like portion 12 carried by the eye portion 10 fits in any one of the notches 6 carried by the jack 5, as is clearly shown in Figures 1 and 2 of the drawing. There is arranged between the dobby jack and the inner periphery of the eye portion 10, at a point directly opposite from the ball-like portion 12 carried thereby, preferably a wedge member 19 made of a yieldable material, preferably rubber, so as to yieldably lock the eye portion 10 on the dobby jack 5.

The outer end of the adjustable member 13 is connected to a flexible connecting member or harness cord 20 which passes over and around the sheaves 4, with the terminals thereof connected to the hooks 8 disposed on the top of the harness frame 7. It is preferable that the flexible member or harness cord 20 be of the type disclosed in the Brickman et al. Patents Nos. 2,211,615 and 2,152,397. The flexible member or harness cord 20 is connected to the adjustable member 13 intermediate the length of the harness cord by folding the same upon itself so as to provide a loop portion intermediate the length thereof. The loop portion is threaded or inserted through the elliptical-shaped hole 17 in the end of the adjustable member 13 and is positioned over and around the hook-shaped portion or wedge hook 18 carried by the adjustable member. It will be seen that the hook-shaped portion 18, together with the hole 17, locks the dobby cord 20 in position so as to prevent either side of the dobby cord from being pulled therethrough or otherwise moved from position, due to the wedging action of the hook-shaped portion.

In the hole 14 arranged on the inner end of the adjustable member 13, there is disposed a yieldable wedge member 21 preferably made of rubber, similar to the wedge member 19, so as to lock the end of the rod-like member 9 in position relative to the adjustable member 13 so as to prevent accidental movement of the same relative to the rod-like member.

In order to adjust the length of the improved harness connector of my invention, so as to raise or lower the position of the harness frame 7 in order to adjust the relation of the shed to the shuttle race, it will be understood that the wedge member 21 is first loosened in or removed from the hole 14. The adjustable member 13 is then moved along the rod-like member 9 until the overall length of the connector is of the desired length. The hook-like portion 16 on the end of the rod-like member 9 is then positioned in the notch 15 of the adjustable member 13 directly opposite thereto. The wedge 21 is then secured in place in the hole 14 so as to lock the adjustable member 13 on the end of the rod-like member 9. If it is desired to adjust the vertical travel of the harness frame 7, it is necessary to adjust the eye portion 10 on the jack 5. This is accomplished by removing or freeing the wedge 19 and moving the eye portion 10 opposite the proper notch 6 in the jack 5 and positioning the ball-like bearing portion 12 in the proper notch. The wedge 19 is then secured in place between the jack 5 and the inner periphery of the eye portion 10 so as to prevent the ball-like portion 12 from being displaced from the notch in which it has been positioned.

As a result of my invention, it will be seen that there is provided a harness connector which consists of a minimum number of wear-producing parts, thus reducing replacement and maintenance costs to a minimum. It will also be seen that the improved harness connector of my invention can be easily and accurately adjusted as to length in order to satisfy any operating condition within the loom. It will be seen also that all the connecting parts of my improved connector are free and flexible, thereby eliminating the danger of any binding action of the parts.

Furthermore, it will be seen that there is provided a harness connector wherein any whipping action is eliminated or reduced to a minimum, thereby eliminating the danger of the displace-

ment of the connector and its adjustable parts from their adjusted and operable position. It will be understood that any whipping action to which my improved connector is subjected will be readily absorbed thereby, due to the construction thereof.

While I have shown and described one specific embodiment of my invention, it will be understood that this embodiment is merely for the purpose of illustration and description and that various other forms may be devised within the scope of my invention, as defined in the appended claims.

I claim:

1. In a loom having a harness actuator, sheave, and frame, a harness connector comprising a longitudinally extending member having an eye portion arranged on one end thereof which fits around the harness actuator for connecting that end of the connector thereto, a wedge-shaped member made of a yieldable material arranged within the eye portion in back of said actuator between the same and the inner side of said eye portion for holding the same yieldably in engagement with said harness actuator whereby a clatterless connection is provided therebetween, means arranged on the opposite end of said longitudinally extending member for adjusting the length thereof, and a flexible member for connecting said adjustable means to the harness frame and extending therefrom over and around the harness sheave.

2. In a loom having a harness frame, sheave, and a harness jack having a plurality of notches arranged along one edge thereof, a harness connector comprising a longitudinally extending member having an eye portion arranged on one end thereof which fits around the harness jack, said eye portion having a ball-like portion arranged on the inner periphery thereof on the side thereof opposite from said longitudinally extending member which is disposed in any one of the notches in said jack, a wedge-shaped member made of a yieldable material arranged within said eye portion in back of said jack between the same and the inner side of said eye portion directly opposite the ball-like portion thereof for holding the ball-like portion yieldably in position in the notch in which it is disposed so that said eye portion is held yieldably in engagement with said jack whereby a clatterless connection is provided therebetween, means arranged on the opposite end of said longitudinally extending member for adjusting the length of the connector, and a flexible member for connecting said adjustable means to the harness frame and extending therefrom over and around the harness sheave.

3. In a loom having a harness frame, sheave, and a harness jack having a plurality of notches arranged along one edge thereof, a harness connector comprising a longitudinally extending rod-like member having an eye portion arranged on one end thereof which is adapted to fit around the harness jack, said eye portion having a ball-like portion arranged on the inner periphery thereof on the side thereof opposite from said rod-like member which is adapted to be disposed in any one of the notches in said jack, a wedge member made of a yieldable material which is adapted to be arranged within said eye portion between the same and said jack directly opposite the ball-like portion of said eye portion for holding the ball-like portion securely in position in the notch in which it is disposed so that said eye

portion is held securely in position on said jack, an adjustable member arranged on the opposite end of said rod-like member for adjusting the length of the connector, said adjustable member having a hole arranged in one end thereof through which said rod-like member is adapted to extend, a hook-like portion arranged on that end of said rod-like member, said adjustable member having a plurality of notches arranged therealong intermediate the length thereof with which the hook-like portion on the end of said rod-like member is adapted to cooperate to lock the adjustable member thereon so as to prevent movement of the same relative thereto, a flexible member for connecting said adjustable member to the harness frame and which is adapted to extend over and around the harness sheave, and means arranged on the end of said adjustable member for connecting said flexible member thereto.

4. In a loom having a harness frame, sheave, and harness jack, a harness connector as defined in claim 3 wherein the means arranged in the end of the adjustable member for connecting the flexible member thereto consists of a hook-like portion arranged on the adjustable member adjacent the end thereof over which the flexible member is adapted to be looped intermediate the length thereof.

5. In a loom having a harness actuator, sheave, and frame, a harness connector comprising a longitudinally extending member having an eye portion arranged on one end thereof which fits around the harness actuator for connecting that end of the connector thereto, means arranged on the opposite end of said longitudinally extending member for adjusting the length thereof, said means having a hole arranged in the outer end thereof with the axis of the hole disposed substantially parallel to that of said longitudinally extending member, a flexible member for connecting said longitudinally extending member to the harness frame and extending over and around the harness sheave, and a hook-shaped portion carried by said adjustable means on the inner side of said hole arranged in the end thereof, said flexible member extending through said hole and attached to said hook-shaped portion.

6. In a loom having a harness actuator, sheave, and frame, a harness connector comprising a longitudinally extending rod-like member having an eye portion arranged on one end thereof which fits around the harness actuator for connecting that end of the connector thereto, an adjustable member arranged on the opposite end of said rod-like member for adjusting the length of the connector, said adjustable member having a hole arranged in the inner end thereof through which said rod-like member is adapted to extend, a hook-like portion arranged on the end of said rod-like member opposite that from said eye portion, said adjustable member having a plurality of notches arranged therealong intermediate the length thereof with which the hook-like portion on the end of said rod-like member is adapted to cooperate to lock the adjustable member thereon in any desired adjusted position so as to prevent movement of the same relative thereto, said adjustable member having another hole arranged in the outer end thereof, a flexible member for connecting said adjustable member to the harness frame and which extends over and around the harness sheave, and a hook-shaped portion carried by said adjustable member on the inner side of said last mentioned hole in said adjustable

member, said flexible member extending through said last mentioned hole and attached to said hook-shaped portion.

7. In a loom having a harness frame, sheave and a harness jack, a harness connector, as defined in claim 6, including a resilient wedge-shaped member arranged in the first mentioned hole of the adjustable member between the rod-like member and the sides of the hole so as to lock the end of the rod-like member in its adjusted position in any one of the notches of the adjustable member.

8. In a loom having a harness frame, sheave, and a harness jack having a plurality of notches arranged along one edge thereof, a harness connector comprising a longitudinally extending member having an eye portion arranged on one end thereof which fits around the harness jack, said eye portion having a ball-like portion arranged on the inner periphery thereof on the side thereof opposite from said longitudinally extending member which is disposed in any one of the notches in said jack, a wedge-shaped member made of a yieldable material arranged within said eye portion in back of said jack between the same and the inner side of said eye portion directly opposite the ball-like portion thereof for holding the ball-like portion yieldably in position in the notch in which it is disposed so that said eye portion is held yieldably in engagement with said jack whereby a clatterless connection is provided therebetween, means arranged on the opposite end of said longitudinally extending member for adjusting the length thereof, said means having a hole arranged in the outer end thereof with the axis of the hole disposed substantially parallel to that of said longitudinally extending member, a flexible member for connecting said longitudinally extending member to the harness frame and extending over and around the harness sheave, and a hook-shaped portion carried by said adjustable means on the inner side of said hole arranged in the end thereof, said flexible member extending through said hole and attached to said hook-shaped portion.

9. In a loom having a harness frame, sheave, and a harness jack having a plurality of notches arranged along one edge thereof, a harness connector comprising a longitudinally extending member having an eye portion arranged on one end thereof which fits around the harness jack, said eye portion having a ball-like portion arranged on the inner periphery thereof on the side thereof opposite from said longitudinally extending member which is disposed in any one of the notches in said jack, a wedge-shaped member made of a yieldable material arranged within said eye portion in back of said jack between the same and the inner side of said eye portion

60

directly opposite the ball-like portion thereof for holding the ball-like portion yieldably in position in the notch in which it is disposed so that said eye portion is held yieldably in engagement with said jack whereby a clatterless connection is provided therebetween, an adjustable member arranged on the opposite end of said longitudinally extending member, said adjustable member having a plurality of notches arranged therealong intermediate the length thereof with which the hook-like portion on the end of said longitudinally extending member cooperates to adjust the length of the connection, said adjustable member having a hole arranged in the outer end thereof, a flexible member for connecting said adjustable member to the harness frame and which extends over and around the harness sheave, and a hook-shaped portion carried by said adjustable member on the inner side of said hole in the adjustable member, said flexible member extending through said hole and attached to said hook-shaped portion.

10. In a loom having a harness actuator, sheave, and frame, a harness connector comprising a longitudinally extending member having a portion arranged on one end thereof which fits around at least part of the harness actuator and which has a surface confronting but spaced from the back of the actuator, a member made of a yieldable material arranged between the back of the actuator and the confronting surface of the connecting portion for holding the harness connector yieldably in engagement with said harness actuator whereby a clatterless connection is provided therebetween, means arranged on the opposite end of said longitudinally extending member for adjusting the length thereof, and a flexible member for connecting said adjustable means to the harness frame and extending therefrom over and around the harness sheave.

11. In a loom having a harness actuator, sheave, and frame, a harness connector comprising a longitudinally extending member having an eye portion arranged on one end thereof which fits around the harness actuator for connecting that end of the connector thereto, a member made of a yieldable material arranged within the eye portion in back of said actuator between the same and the inner side of said eye portion for holding the harness connector yieldably in engagement with said harness actuator whereby a clatterless connection is provided therebetween, means arranged on the opposite end of said longitudinally extending member for adjusting the length thereof, and a flexible member for connecting said adjustable means to the harness frame and extending therefrom over and around the harness sheave.

ALAN E. BRICKMAN.
